DESK MEMORANDUM CALENDAR

John P. Wege, St. Paul, Minn., assignor to
 Brown & Bigelow, St. Paul, Minn., a corpora-
 tion of Minnesota

Application February 8, 1937, Serial No. 124,597

3 Claims. (Cl. 281—17)

My invention relates to an improvement in desk memorandum calendars adapted to provide a calendar means and a memorandum means combined in a simple and attractive unit.

Memorandum pads of various types have been in common use for many years. The present invention, however, is designed to combine a calendar such as is usually found on a desk with a memorandum pad, in a single unit which may be folded to conceal a portion of the indicia thereon when it is so desired. My invention includes a supporting means for a calendar which may be changed from year to year, a pad for appointments whereby a list of appointments may be maintained for days or weeks in advance, and a memorandum pad upon which notations may be made which are to be given to some member of the office staff, or to be maintained in a separate file.

It is a purpose of my invention to provide a device formed of leather or other suitable material, which is folded along a line offset from the center of the same to permit one portion thereof to overlap another portion of the same to conceal a list of appointments or other notations from the eyes of the public. This construction permits a memorandum pad to be revealed at all times, constantly accessible for use in preparing memorandum of any desired type. If these memorandums are designed to be torn off from the pad as they are completed, no harm may result from this portion of the pad being displayed at all times.

It is a further purpose of my invention to provide a combined calendar and memorandum device wherein the calendar and the portion of the device designed to contain a list of days activities or appointments throughout an entire week, are normally concealed thus protecting these parts from dust and dirt. In this way the calendar and appointment pad or list may be maintained throughout a long period of time without ill effects.

It is a further purpose of my invention to provide a support for a calendar, an appointment list pad, and a memorandum pad, each of which is readily removable and is replaceable secured to the support. In this way, I provide a device which may be maintained through a number of years by merely changing the calendar and pads from time to time.

These and other objects and novel features of my invention will be more clearly and fully set forth in the following specification and claims:

In the drawing forming a part of my specification:

Figure 1 is a perspective view of my memorandum pad in closed position.

Figure 2 is a plan view of my memorandum pad in open position.

Figure 3 is a cross-sectional view on the line 3—3 of Figure 2.

Figure 4 is a sectional view similar to Figure 3 with the pads and calendar removed.

My calendar A comprises a base 10 having secured thereto a flap cover portion 11 which is adapted to fold over and to overlap partially the base 10 when the device is in closed position. The device may be seen in this closed position in Figure 1 of the drawing.

Figures 3 and 4 of the drawing best illustrate the construction of the calendar and memorandum pad. For the purpose of illustration the thickness of the various elements forming the combination has been greatly exaggerated. The calendar A is provided with a base portion 10 which includes a reinforcing board 12. Upon this board 12 are superimposed two pockets which are closed along opposite sides and which are open at one end to receive the anchoring stub or flap of the memorandum and appointment pads. To form these pockets which are designated as 13 and 14 respectively, I provide a reinforcing sheet 15 which extends from one edge 16 of the board 12 to a point adjacent the opposite edge 17 thereof. A shorter reinforcing member 18 extends from the edge 16 of the board 12, a lesser distance to form the pocket 13. The reinforcing sheets 15 and 18 are bound along the side edges 19 and 20 of the base 10 by a binding tape 21 which conceals the edges of the board 12, and which folds over the top and bottom of this board and over the side edges of the reinforcing sheets 15 and 18 throughout their length. For the sake of appearance lining sheets 22 and 23 respectively are adhered over the exposed surfaces of the reinforcing sheets 15 and 18 and over the adjacent portions of the binding tape 21 to conceal these elements. The lining sheets 22 and 23 extend the width of the base 10 between the edges 19 and 20. Overlying the board 12 and the tape 21 along the edge 17 of the board 12, I provide a cover sheet 24. Superimposed over the secured edge of the sheet 24, I provide an inner lining sheet 25. The sheets 24 and 25 are secured to the board 12 by stitching 26 which extends through the lining sheet 25, the cover sheet 24, the board 12 and the tape 21. A bottom covering sheet 27 extends beneath the board 12 and is secured

thereto. This sheet is substantially the dimensions of the board 12, and conceals the board 12 to which it is secured. The seams between the tape 21 and the board 12 are also concealed by this bottom cover sheet 27.

5 A heavy reinforcing board 28 is secured to the surface of the cover sheet 24, this cover sheet extending over one entire surface of the board 28 and folding over the free edge 29 of the board 10 28. The lining sheet 25 overlies the opposite edge 30 of the board 28, and is adhered thereto. A pocket 31 covers the exposed surface of the board 28 overlapping the folded edge 32 of the covering sheet 24 and the edge of the sheet 25. 15 The pocket 31 includes a reinforcing member 33 having a covering sheet 34 adhered over one entire surface thereof and having the edges thereof folded over the other surface of the same. A relatively narrow reinforcing sheet 35 having a 20 covering member 36 extending over the outer surface thereof and having an edge 37 folded over the opposite surface thereof, is wrapped about one edge 38 of the reinforcing sheets 35 and 33 and over the edge of the covering sheet 25 34. The pocket is formed between the reinforcing sheet 35 and the covering sheet 34.

The device illustrated is for the purpose of supporting a memorandum pad 40 and appointment pad 41 and a calendar sheet 42. The calendar sheet 42 is inserted into the pocket 31. The memorandum pad 41 is provided with an anchoring tongue 43 which extends into the pocket 14. The memorandum pad 40 is provided with an anchoring tongue 44 which extends into the pocket 13. In this way the pads 40 and 41 are held in place with respect to the support in a simple and effective manner.

In adhering the lining member 25 to the cover sheet 24, it is possible to adhere these two parts together while in folded position. When this procedure is followed the lining 25 is stretched as the flap cover 11 is opened, and a tendency

is created to hold the cover 11 in closed position. Accordingly unless the cover 11 is laid down flat as shown in Figures 3 and 4, there is a considerable force tending to close this cover 11 to overlie the pad 41. The board 28 may be formed of metal if desired to provide a weighted top tending to hold the appointment pad 41 flat against the base portion 10. The cover flap 11 in this way acts as a paper weight as well as a cover to hold the sheets of the pad 41 in proper 10 position.

In accordance with the patent statutes, I have described the principles of operation of my desk memorandum calendar and while I have endeavored to illustrate the best modifications 15 thereof, I desire to have it understood that these are only illustrative of a means of carrying out my invention and that changes may be made within the scope of the following claims without departing from the spirit of my invention.

20 I claim:

1. A memorandum pad support comprising a base portion, a pair of pads mounted thereon, a cover portion hingedly secured thereto, said cover extending a fraction of the total length of said 25 base portion, extending over one pad and leaving the other exposed, and paper weight means enclosed in said cover.

2. A memorandum pad support comprising a rigid base portion, pockets formed therein, 30 memorandum pads, tongues on said memorandum pads each adapted to extend into a pocket in said base portion, and cover means flexibly secured to said base portion to overlie one pad and to leave the remainder exposed.

3. A desk memorandum pad including, a rigid base portion, a series of pads removably secured thereto, a cover portion flexibly secured along one edge of said base portion, said cover extending over one of said memorandum pads and 40 leaving the other exposed.

JOHN P. WEGE.
